(57) **CLAIM**

The ornamental design for a lens for automobile lamp as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of the lens for automobile lamp showing our new design.

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top front left perspective view thereof; and,

FIG. 8 is a rear side perspective view thereof.

1 Claim, 3 Drawing Sheets
